ATTORNEY

UNITED STATES PATENT OFFICE

SIGMUND SPIELBERGER, OF JAMAICA, NEW YORK

SUSPENDER VEST

Application filed March 8, 1930. Serial No. 434,210.

This invention relates to new and useful improvements in a combination vest and trouser supporter.

The invention has for an object the provision of a device of the class mentioned, which is of simple durable construction, dependable in use and efficient in action, and which can be manufactured and sold at a reasonable cost.

10 The invention proposes a vest having a lining consisting of a pair of chest portion lining sections and a back portion lining section, and each of said lining sections comprising outer and inner sheets secured together, and straps between said inner and outer sheets and attached at their top ends to the lining in the vicinity of the shoulders of the vest and extending thru slots in the inner sheets substantially midway between the shoulders and the bottom of the vest and the vertical edges of the chest portions and terminating at their free ends in means for supporting a pair of trousers.

25 The invention also proposes a means for transmitting tension from said supporting straps to the lining for urging different portions of the lining against a wearer of the device to change its feel on the person and consequently the comfort.

30 A device constructed according to this invention presents a construction with several novel features. It necessitates discarding of suspenders when the vest is not worn. The present day rules of etiquette are such that it is impolite to wear suspenders exposed, and the temptation to break this rule is very strong. This device eliminates such temptations. It also permits the opening of the vest, but limits such opening to a small amount so that the suspenders themselves do not show.

45 For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a front elevational view of a vest constructed according to this invention.

Fig. 2 is an elevational view of the inner side of the chest portion lining section used in Fig. 1. 55

Fig. 3 is an outer view of the lining section shown in Fig. 2.

Fig. 4 is a vertical sectional view taken on the line 4—4 of Fig. 3.

Fig. 5 is a vertical sectional view taken on the line 5—5 of Fig. 3. 60

Fig. 6 is a view similar to Fig. 1, but showing one side of the vest moved completely open to disclose the interior thereof, and illustrating a modification of the invention. 65

Fig. 7 is a view similar to Fig. 4, but illustrating another modified form of the device.

Fig. 8 is a view similar to Fig. 2, but disclosing the form of the device shown in Fig. 7. 70

The combination vest and trouser supporter consists of a vest 10 having a lining 11 consisting of a pair of chest portion lining sections 12 and a back portion lining section 13, and each of said chest portion lining sections comprising an outer sheet 14 secured to an inner sheet 15, and straps 16 between said outer and inner sheets and attached at their upper ends 17 to the lining in the vicinity of the shoulders 18 of the vest and extending thru slots 19 in the inner sheets 14 substantially midway between the shoulders and the bottom of the vest and the vertical edges 20 of the chest portions and terminating at their free ends 21 in means for supporting a pair of trousers. 75 80 85

The vest 10 is of conventional design and construction and opened at the front. One of the edges of the opening is provided with buttons 22 engageable in button holes 23 in the other edge for closing the vest. The vest 10 is also provided with pockets 24 constructed in ordinary fashion. In Figs. 2 to 5 inclusive, a detail has been shown of one of the chest portion lining sections. This detail particularly brings out that the outer and inner sheets 14 and 15 respectively are secured together by stitches 25 along the edges and extending from the front edge of the lining section up across the shoulder 100

portion and then downwards part of the way along the back portion. The inner and outer sheet sections are not secured together along the bottom so as to be open as indicated in Fig. 5 by reference numeral 26. The outer sheet 15 is substantially one half the height of the sheet 14.

The straps 16 are preferably made from cloth, elastic or other similar material. Fig. 4 particularly points out that the straps are arranged between the inner and outer sheets 14 and 15 respectively and extend out thru the slot 19 in the inner sheet 14. Stitches 27 serve to attach the top ends of the strap 16 to the shoulder portions of the lining sections. Each slot 19 is trimmed with a panel portion 28 clearly shown in Fig. 2 to eliminate a rough bottom edge. A small section of the bottom portion of the inner sheet 15 is attached as at 29 by stitches 30 to the top edge of the slot 19. This is clearly shown in Fig. 4. Consequently, along the line 4-4 of Fig. 3 the outer and inner lining sections are connected.

The means for supporting a pair of trousers upon the free ends of the straps 16 consists of clamp members 32 adjustably mounted along the length of each of the straps and provided with a loop portion 33 holding a flexible cable 34 terminating at each end in button engaging members 35. These button engaging members have upper large portions for engaging over a button and reduced bottom ends for engaging the threads securing the buttons in place.

When the vest shown in Fig. 1 is worn and the members 35 are engaged upon the buttons of one's trousers, or a strap on one's trousers engaged thru the members in lieu of the buttons, the weight of the trousers is transmitted along the straps to the shoulder portions of the vest and around the back of the wearer's neck. This acts as a yoke upon one's neck for supporting the trousers. Particular attention is called to the fact that the strap 16 is free to assume inclined positions with the points of attachment 27 as centers. Dot and dash lines 36 in Fig. 2 indicate inclined positions as limited by the size of the slot 19. This arrangement compensates for different locations of the buttons upon the trousers. In addition, it allows the buttons to be so arranged on the trousers as to get the most comfortable suspension.

In Fig. 6 a modified form of the invention has been disclosed in which the back portion lining section 13 is constructed very similar to the chest portion lining sections, that is, it is composed of an outer and an inner sheet, and straps 16 arranged between these sheets and extending out from slots 19 towards the inner sides of the vest. These straps are attached at their top ends upon the shoulder portions. In use, the support-

ing means upon the bottom of the straps on the back portion lining sections are attached to buttons along the rear of one's trousers, while the front supporting means, that is, the means upon the bottom of the straps on the chest portion lining sections are attached upon buttons on the front of the trousers. Necessarily, the trousers are now supported across the shoulders instead of across the back of one's neck as in the preferred form. Some people may prefer this arrangement, deeming it greater comfort. In other respects the details of construction are similar to the preferred form.

In Figs. 7 and 8 another form of the device has been illustrated in which a means is provided for transmitting tension from said supporting straps to the lining for urging different portions of the lining against a wearer of the device to change its feel on the person and consequently the comfort. This means consists of snap fastener elements 37 attached along the length of the straps 16 and engageable in complementary snap fastener elements 38 attached upon the sheets forming the lining. These snap fastener elements are engageable with each other. Normally, they are out of engagement and in this condition the pull of supporting the trousers is transmitted to the shoulder portions of the vest. In the event that the point of suspension is to be changed, it is merely necessary to engage certain of the snap fastener studs with their sockets. For example, if the snap fastener stud and socket indicated in Fig. 8 by reference numeral 39 were engaged, then suspension will occur at this particular point. Further, the inclination which the bottom portion of the strap 16 may assume is limited as indicated by the dot and dash lines 40. This changes the feel upon the wearer and theoretically comforts.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A combination vest and trouser supporter, comprising a vest having a lining consisting of a pair of chest portion lining sections and a back portion lining section, and each of said chest portion lining sections comprising outer and inner sheets secured together, straps between said inner and outer sheets and attached at their top ends to the lining in the vicinity of the shoulders of the vest and extending thru slots in the inner sheets substantially at their centers and terminating at their free ends in means for sup-

porting a pair of trousers, and means for transmitting tension from said supporting straps to the lining for urging different portions of the lining against a wearer of the device to change its feel on the person and consequently its comfort.

2. A combination vest and trouser supporter, comprising a vest having a lining consisting of a pair of chest portion lining sections and a back portion lining section, and each of said chest portion lining sections comprising outer and inner sheets secured together, straps between said inner and outer sheets and attached at their top ends to the lining in the vicinity of the shoulders of the vest and extending thru slots in the inner sheets substantially at their centers and terminating at their free ends in means for supporting a pair of trousers, and means for transmitting tension from said supporting straps to the lining for urging different portions of the lining against a wearer of the device to change its feel on the person and consequently its comfort, comprising snap fastener elements attached upon the straps and engageable with complementary snap fastener elements attached upon the lining.

3. A combination vest and trouser supporter, comprising a vest having a lining consisting of a pair of chest portion lining sections and a back portion lining section, and each of said chest portion lining sections comprising outer and inner sheets secured together, straps between said inner and outer sheets and attached at their top ends to the lining in the vicinity of the shoulders of the vest and extending thru slots in the inner sheets substantially at their centers and terminating at their free ends in means for supporting a pair of trousers, and means for transmitting tension from said supporting straps to the lining for urging different portions of the lining against a wearer of the device to change its feel on the person and consequently its comfort, comprising snap fastener elements attached upon the straps and engageable with complementary snap fastener elements attached upon the lining, the ends of said slots and the points of suspension of said straps limiting the possible angular positions of said straps.

In testimony whereof I have affixed my signature.

SIGMOND SPIELBERGER.
